UNITED STATES PATENT OFFICE

ALONZO ALDRICH, OF BELOIT, WISCONSIN

FOURDRINIER PAPER MACHINE

Application filed July 2, 1923. Serial No. 848,961.

My invention relates to paper making machines, particularly of the Fourdrinier type.

One of the objects of the invention is to provide a simple, practical and advantageous machine of the class specified.

Another object of the invention is to provide a Fourdrinier machine wherein the table may be bodily moved or removed laterally to permit application of a new wire, and may also be shaken to improve the fibre and may also have its feed end adjusted vertically to control the character of the fibre.

Another object of the invention is to arrange for the proper and cooperative operation of the table, shaking mechanism and pulp holding and feeding devices in carrying out the foregoing operations.

Other objects of the invention will appear and be pointed out hereinafter.

20 In the accompanying drawings, Fig. 1 is a side elevation of a Fourdrinier paper making machine embodying my present invention;

Fig. 2 is a cross section taken on line 2—2 in Fig. 1, showing the table in normal position;

Fig. 3 is a similar view, with the table removed to permit changing a wire;

Fig. 4 is a cross section taken on line 4—4 in Fig. 1, on an enlarged scale;

30 Figs. 5 and 6 are sections taken on line 5—5 and 6—6, respectively, in Fig. 4;

Fig. 7 is a cross sectional view taken on line 7—7 in Fig. 1;

Fig. 8 is a view of a detail of construction;

35 Fig. 9 is a section taken on line 9—9 in Fig. 7;

Fig. 10 is a cross section taken on line 10—10 in Fig. 1;

Fig. 11 is a plan view of mechanism shown 40 in Fig. 10;

Fig. 12 is a side elevation of feed end of table;

Fig. 13 is a section on line 13—13 in Fig. 45 10;

Fig. 14 is a plan view of the table and rolls thereon;

50 Fig. 15 is a side elevation of the feed end of the table and the pulp holding and feeding devices;

Fig. 16 is a cross section taken on line 16—16 in Fig. 15;

Fig. 17 is a cross section taken on line 17—17 in Fig. 15, on an enlarged scale;

Fig. 18 is a cross section taken on line 55 18—18 in Fig. 16;

Fig. 19 is a vertical section taken on line 19—19 in Fig. 16;

Fig. 20 is a view showing the tracks and rollers thereon;

Fig. 21 is a cross section taken on line 21—21 in Fig. 20;

Fig. 22 is a cross sectional view of one side of the table; and

Fig. 23 is a plan view of the mechanism 65 shown in Fig. 22.

Referring to the drawings, I show a Fourdrinier machine having a main table portion 1 supporting rolls 2 for the wire 3. An additional or supplemental end portion 1^a is 70 also embodied in the machine shown, the same supporting vacuum boxes 5—5 and 6—6 and having a jointed connection, as by pivot 7, with the main portion 1, and also having rolls 8—8 and 9—9 for the wire. 75

The table comprising the sections or portions 1 and 1^a is adapted for bodily removal in a sidewise manner, to permit the advantageous application of a new wire after a used one has been removed. To such end 80 provision is made for moving the table out and back sidewise on tracks 11, 12 and 13, the table being shown in normal position in Fig. 2, and moved out on said tracks in Fig. 3. The table is provided with suitable power 85 mechanism for moving it out and back on said tracks, as for example, an electric motor 15 (Figs. 1 and 5), power connected by spur wheel 16, gear 17, worm 18 and wheel 19 with driving shaft 20 carrying wheel 21 for track 90 13, said shaft 20 being coupled to shaft 20^a carrying wheels 22 and 23 for tracks 11 and 12, respectively. The rear or back side of the table is provided with wheels 25—25 (Figs. 2, 4 and 6), for traveling on the tracks 95 11, 12 and 13, said wheels 25 being preferably constructed, as shown in Fig. 6, with outside portions 25^a—25^a for purposes to be described later.

Tracks 11, 12 and 13 are preferably con- 100

tinuous and of such length as to provide for the table in both out and in positions and are supported by posts or pedestals 26, 27, 28 and 29. Posts 27 have means such as bolts 30, for adjusting tracks vertically, and other means such as bolts 31 and 32 for adjusting and holding same in vertical position. Posts 28 have adjustable members 33 carrying rollers 33^a for supporting tracks, and bolts 34—34 for vertically adjusting members 33 and thereby the tracks; also bolts 32—32 for maintaining tracks in vertical position. Posts or pedestals 28 have top surfaces which are inclined slightly upward to elevate rollers 25 and thereby permit tracks to be removed. Post 29 has a wheel 29^a for serving as a stop to limit backward movement of table. Posts 27 and 28 are preferably connected together in pairs by cross beams 40.

20. Thus it will be seen that the entire table may be moved out to permit changing wire by operating motor 15, and then moved back by reversing the motor, front edge of table normally resting with wheels 21, 22 and 23 on tracks 13, 11 and 12, respectively, and rear of table resting with wheels 25 on track surfaces 37 of pedestals 28.

30. The mechanism for shaking the table disclosed herein is shown more particularly in Figs. 1 to 11, inclusive. It includes a series (four are shown, Fig. 1) of upwardly extending reciprocating or vibratory members 43—43 mounted on rock shaft 44, which is supported by bearings 45—45 located on the floor, whereby shaft 44 is low and vibration is prevented. Upright members 43 are connected with table section 1 by detachable connections permitting table to be shaken as desired, and also permitting detachment or disconnection of shaking mechanism to allow removal of table in direction away from such mechanism for applying new wire.

40. The connections between the two middle members 43 and table are shown in Figs. 2 and 15. They comprise straps 51 connected to yokes 52 which are on opposite sides of uprights 43, yoke members 52^a sliding between rolls 53—53 on boxes 54 which enclose uprights 43 and are also connected with straps 51. Boxes 54 are provided with openable sides 55 normally held in position so as to engage upright 43 by bolt 56 and hand nut 57. By unscrewing latter, side 55 may be swung about pivot bolt 58 so as to open box 54 and allow separation of same from upright 43. The connection for the right hand end member 43 is shown in Figs. 17 and 18. It comprises a strap 51 such as previously described, but same has a pivotal connection 59 with the jointed section 1^b of the table, and also a connection 60 with the shaking section 1 of the table, whereby both sections are shaken. The connection for the left hindmost member 43 is shown in Figs. 3 and 4. It 60 comprises a box 61, open at one side and hav-

ing an inclined side and a connection 63 for the brest roll bearing 64. Section 1 of table is mounted on flexible members 41 whose lower ends are secured to channel members 42, to permit shaking of rolls 2 and wire thereon without shaking the remainder of the table. 70

Vibratory members 43 are actuated by rocking of shaft 44 by vertically vibrating arms 47 actuated by reciprocating members 47^a controlled by shaft 47^b which is turned by gear connection with power shaft 48, so that rotation of latter will vibrate members 43 and so shake table. 75

Thus the whole table section 1 and brest roll also may be shaken as desired and also 80 detached from shaking mechanism to permit removal of table for applying new wire, as shown in Figs. 2 and 3.

Inasmuch as table is preferably shaken by 85 shaking mechanism, table sections 1 and 1^a are preferably mounted at upper ends of flexible members 41—41 whose lower ends are connected to and supported by side channel members 42—42, below which the various 90 track wheels 21, 22, etc. are mounted, whereby 90 table member 1 may be shaken relatively to members 42—42. The shaking mechanism shown herein comprises a vibratory member 43 mounted on a rock shaft 44 operated by vibratory member 47 actuated by driving 95 members 48 and 49. Inasmuch as said shaking mechanism is shown, described and claimed in another application of mine, executed of even date herewith, Serial No. 648,962, filed July 2, 1923, Shaking mechanism for Fourdrinier machines, it will not be further described nor claimed herein. 100

In accordance with present invention, the feed end of the table and the pulp holding and feeding devices may be adjusted vertically and in such relation as to cooperate properly in their various adjustments. This adjustment may be secured by means of suitable elevating devices and connections for accomplishing the desired purposes. As an 110 advantageous arrangement I have shown an electric motor 65 mounted on the top member 66 forming with posts 67^a framework on which the pulp holding and feeding devices are mounted. Motor 65 is geared to power 115 shaft 68 so as to drive same and shaft 68 is connected by sprocket chain 69 with supplemental power shaft 70. The power shafts 68 and 70 raise and lower the feed end of the table 1 and feed box 71 through suitable 120 mechanism preferably controlling same, so that they shall rise and fall together in proper relationship, and also so that the feed box shall be tilted toward the table as it rises and restored to level position as it falls. The 125 mechanism shown for accomplishing this result comprises two sets of vertically adjustable yokes 73—73, and 74—74 whereof the yokes 73—73 are raised and lowered by plunger 73^a, having a worm and wheel con- 130

nection with shaft 68, and whereof yokes 74—74 are actuated by plunger 74*, having similar worm and wheel connection with shaft 70.

5 Yokes 73 are connected with hangers 76 which engage the ends of projecting members 77 on a cross beam 78 which extends underneath and engages feed box frame pieces 79—79, so that raising and lowering of yokes 73 will elevate and lower feed box 71.

10 Yokes 74 are connected with hangers 80 whose lower ends engage projections 81 on the feed end of table section 1, whereby raising and lowering of yokes 74 will raise and lower feed end of table, whereby it will be seen feed box 71 and feed end of table will rise and fall together.

15 As a matter of further and specific improvement, provision is made for tilting feed box 71 so that it will incline down toward the table as it and the table rise. For this purpose I show guideways 83—83 and 84—84 on end posts 67 and slide pins or rollers 85 and 86, the former on side frames 87 on feed 20 box 71, and the latter on frames 88 on hangers 88* extending down below feed box 71, being preferably formed integral with frames 79. Guideways 83 are preferably inclined inwardly and upwardly, and guideways 84 outwardly and upwardly, as shown in Fig. 7, whereby feed box 71 will in effect be tilted substantially about the feed end of table as both rise and fall, thus insuring proper feed 25 of pulp and proper cooperation of devices in the upward and downward adjustment. Guideways 83 may be adjusted by screw bolts 83* and guideways 84 by screw bolts 84*.

30 The brest roll on table is preferably made adjustable lengthwise of the table to facilitate applying a new wire and for other purposes. In the arrangement shown, said roll is mounted on slides arranged to slide in guideways 92 and provided with a rack 93 meshing with a pinion 94 on shaft 95 also 35 carrying gear 96 meshing with pinion 97 turned by handle 98, whereby rotation of handle 98 will adjust brest wheel 90 lengthwise of the table. Certain subject matter is disclosed and claimed broadly in my co- 40 pending applications, Serial No. 595,258, filed Oct. 18, 1922; Serial Nos. 648,959, 648,960 and 648,962, filed July 2, 1923; and Serial No. 205,006, filed July 11, 1927.

45 It will be understood that changes and modifications may be made without departing from the spirit of the invention.

What I claim is:

1. A Fourdrinier machine having a laterally removable, shakable and vertically adjustable table combined with power means for shaking the table adapted to permit the removal and vertical adjustment of the table.

2. A Fourdrinier machine having a laterally removable, shakable and vertically adjustable table combined with power means

for laterally removing the table and for shaking same said shaking means being adapted to permit the removal and vertical adjustment of the table.

3. A Fourdrinier machine having a laterally removable, shakable and vertically adjustable table combined with power means for shaking the table and for vertically adjusting same said shaking means being adapted to permit the removal and vertical adjustment of the table.

4. A Fourdrinier machine having a laterally removable, shakable and vertically adjustable table and power means for laterally removing, shaking and vertically adjusting same said shaking means being adapted to permit the removal and vertical adjustment of the table.

5. A Fourdrinier machine having a laterally removable, shakable and adjustable table and shaking means adapted to permit the removal and adjustment of the table.

6. A Fourdrinier machine having a laterally removable, shakable and vertically adjustable table, and also having paper material holding and feeding devices vertically adjustable to cooperate with the table, means for laterally removing the table adapted to permit adjustment thereof and of the paper material holding and feeding devices, and means for shaking the table adapted to permit the removal and vertical adjustment of the table.

7. A Fourdrinier machine having a laterally removable, shakable and vertically adjustable table, and also having paper material holding and feeding devices vertically adjustable to cooperate with the table, means for adjusting the table and paper material holding and feeding devices adapted to permit removal of the table, and means for shaking the table adapted to permit the removal and vertical adjustment of the table.

8. A Fourdrinier machine having a laterally removable, shakable and vertically adjustable table and also having vertically adjustable paper holding and feeding devices, means for raising and lowering said table and said devices in unison, and means for shaking the table adapted to permit the removal and vertical adjustment of the table.

9. A Fourdrinier machine having a laterally removable, shakable and vertically adjustable table and also having vertically adjustable paper holding and feeding devices, means for raising and lowering said table and said devices in unison, said means being adapted for connection with and disconnection from the table to permit lateral removal of same, and means for shaking the table adapted to permit the removal and vertical adjustment of the table.

10. A Fourdrinier machine having a laterally removable, shakable and vertically adjustable table, means for removing the table

and adjusting means for vertically adjusting the feed end of the table, said means being detachably connected with the table, and means for shaking the table adapted to permit the removal and vertical adjustment of the table.

11. A Fourdrinier machine having a laterally removable, shakable and vertically adjustable table, means for removing the table and adjusting means for vertically adjusting the feed end of the table, said means being detachably connected with the table and comprising vertically adjustable members, means for elevating and lowering the same, and means for shaking the table adapted to permit the removal and vertical adjustment of the table.

12. A Fourdrinier machine having a laterally removable, shakable and vertically adjustable table, means for removing the table and adjusting means for vertically adjusting the feed end of the table, said means being detachably connected with the table and comprising vertically adjustable members, means for elevating and lowering the same, means for vertically adjusting the paper material holding and feeding devices, and means for shaking the table, said shaking means having connections with the table adapted to permit the table to be vertically adjusted and removed.

13. A Fourdrinier machine having a laterally removable, shakable and vertically adjustable table, means for removing the table and adjusting means for vertically adjusting the feed end of the table, said means being detachably connected with the table and comprising vertically adjustable members, means for elevating and lowering the same, means for vertically adjusting the paper material holding and feeding devices, said means comprising yokes engaging the supporting frame of the paper material holding and feeding devices, means for adjusting said yokes, and means for shaking the table, said last means being so connected to the table as not to interfere with the use of said first means.

14. A Fourdrinier machine having a laterally removable, shakable and vertically adjustable table, and also having vertically adjustable paper material holding and feeding devices, means for adjusting said table and paper material holding and feeding devices vertically in unison, and means for shaking the table, said shaking means having connections with the table adapted to permit the table to be vertically adjusted and removed.

15. A Fourdrinier machine having a laterally removable, shakable and vertically adjustable table, and also having vertically adjustable paper material holding and feeding devices and means for adjusting said table and paper material holding and feeding devices vertically in unison, said means comprising a power generator and connections

between the same and said raising and lowering mechanism, and means for shaking the table, said shaking means having connections with the table adapted to permit the table to be vertically adjusted and removed.

16. A Fourdrinier machine having a laterally removable, shakable and vertically adjustable table, and shaking means comprising vibratory members detachably and adjustably connected to said table.

17. A Fourdrinier machine having a laterally removable, shakable and vertically adjustable table, and also having paper material holding and feeding devices vertically adjustable to cooperate with the table, and shaking means comprising vibratory members detachably and adjustably connected to said table.

18. A Fourdrinier machine having a laterally removable, shakable and vertically adjustable table, means for laterally removing the table adapted to permit adjustment thereof, and shaking means comprising vibratory members detachably and adjustably connected to said table.

19. A Fourdrinier machine having a laterally removable, shakable and vertically adjustable table, and also having paper material holding and feeding devices vertically adjustable to cooperate with the table, means for adjusting the table and paper material holding and feeding devices adapted to permit removal of the table, and shaking means comprising vibratory members detachably and adjustably connected to said table.

20. A Fourdrinier machine having a laterally removable, shakable and vertically adjustable table, means for removing the table and adjusting means for vertically adjusting the feed end of the table, said means being detachably connected with the table and comprising vertically adjustable members, means for elevating and lowering the same, means for vertically adjusting the paper material holding and feeding devices, and shaking means comprising vibratory members detachably and adjustably connected to said table.

21. The combination with a detachable vertically adjustable and shakable table, of means for removing the table adapted to permit adjustment and shaking thereof, means for adjusting the table adapted to permit removing and shaking thereof, and means for shaking the table adapted to permit removal and adjustment thereof.

In witness whereof, I hereunto subscribe my name this 26th day of May, A. D., 1923.

ALONZO ALDRICH.
